UNITED STATES PATENT OFFICE.

JOHN H. GALLOUPE, OF DENVER, COLORADO, ASSIGNOR TO THE GALLOUPE SHALE PROCESS COMPANY, OF GRAND JUNCTION, COLORADO, A CORPORATION OF COLORADO.

VERTICAL OIL-SHALE-TREATING RETORT.

1,365,822.

Specification of Letters Patent.

Patented Jan. 18, 1921.

Application filed August 18, 1919. Serial No. 318,342.

To all whom it may concern:

Be it known that I, JOHN H. GALLOUPE, a citizen of the United States of America, residing at the city and county of Denver and State of Colorado, have invented a new and useful Vertical Oil-Shale-Treating Retort, of which the following is a specification.

My invention relates to a new vertical oil-shale treating retort and coöperating gas condensing apparatus; for the recovery of petroleum oil and other products therefrom. And the objects of my invention are:

First: To provide a vertical retort for giving a roasting and sublimating treatment to oil-bearing shale rock;

Second: To provide a vertical retort for hydro-carbons and for separating from oil-bearing shale its various constituent elements such as petroleum oil, bitumens, hydro-carbons, and such other volatile elements as exist in oil shale rock;

Third: To provide means for sublimating and condensing the various gases liberated from oil shale during its roasting and sublimating treatment in my retort;

Fourth: To provide a vertically positioned retort, adapted to give to oil shales a progressive and constantly heat increasing roasting and volatilization treatment that effectively separates all of the elements from oil shale and then to condense the several volatile gases and elements liberated in my retort and recover them in a commercially useable form.

I attain these objects by the mechanism illustrated in the accompanying drawings in which:

Figure 1, is a vertical sectional elevation through the center of my retort, and a side elevation of the condensing apparatus that forms a coöperating part of it.

Fig. 2 is a horizontal sectional view thereof on the line 2—2 of Fig. 1, the temporary brick-work closing the entrance to the stack, being removed.

Fig. 3 is a horizontal sectional view on the line 3—3 of Fig. 1.

Fig. 4 is an enlarged vertical sectional view of the lower portion of the retort showing the conveyer for removing the material that reaches the lower end of the retort.

Fig. 5 is a sectional perspective view of one of the sections of the cylinder of the retort.

Fig. 6 is a perspective view of the upper end portion of the inner cylinder. 55

Fig. 7 is a vertical sectional view of the operating sprocket wheel which is secured to the inner cylinder.

Fig. 8 is a plan view thereof.

Fig. 9 is a plan view of the stationary circular feed spout at the upper end of the retort, and 60

Fig. 10 is a bottom plan view of the ring secured to the inner tube, having plows or scrapers for removing the shale from the 65 bottom of the spout, into the retort.

Similar letters of reference refer to similar parts throughout the several views.

Referring to the drawings: The numeral 1 designates a brick fire box, within which 70 a fire wall 2. is built, fuel supporting grates 3. are positioned in the fire box, and a fuel entrance door 4. is placed in the front wall 5. of the fire box above the grates, and an ash pit door 6. is also placed in the front 75 wall of the fire box below the grates.

The top of the fire box is covered by a brick arch 7. which extends from the front wall 5. back to and is built into the adjacent side of the retort 8. which projects vertically 80 above the fire box from a concrete foundation 9. that extends also under the fire box.

My new vertically disposed oil-shale treating retort is preferably of circular construction and it projects above the fire box about twenty feet to forty feet by five feet in diameter for tonnage capacities of from about one hundred to two hundred tons per day. 90

My oil-shale treating retort comprises an outside cylindrical casing 8. that is preferably made of brick and an inner tubular flue 10. the outside surface of which is provided with short spirally arranged shelves 95 11. this inner stack tube is preferably constructed of cast iron but may be made of sheet iron or any other suitable material, the shelves 11. are preferably arranged in four spiral groups that extend entirely around the 100 tube from one end to the other; they comprise thin radially projecting ledge portions that extend to within a slight distance of the face of the surrounding cylinder; the length of the ledges of each group, being 105 slightly less than the length of the space be-

tween them, and they are also arranged to overlap each other, and at the same time to stand individually in a substantially horizontal position although if preferred they 5 could be inclined slightly downward from the oil shale feeding-in end.

The inner flue 10, with its multiplicity of separated and independent shelves, constitutes the principal heat-receiving, heat-retaining, and heat-radiating element of the 10 retort, and also its principal shale receiving and sublimating member. Its lower end is connected by a heat-conveying flue with the bottom portion of the fire box, as will be 15 hereinafter described, and the exit at the upper end of the flue is controlled by a damper 13, mounted in a stack 14, which is secured to the upper end of the said flue, as will be hereinafter fully described.

20 For convenience in handling and also in casting I preferably make this inner tubular shelf smoke stack member, which I will hereinafter call the shelf tube, in sections of preferably about four feet long, one of the 25 ends of each section of which fits over a projecting end made on the end of another similar section and is secured thereon by set screws 15.

This inner tubular stack member 10, is 30 surrounded loosely by a cast iron cylindrical housing 18, that is also made for convenience in handling in sections 19., each of which has an annular rim 20, at one end, and a slight annular flange 21, at its opposite 35 end, that is of a diameter to fit inside the rim 20, and thus permit the sections to be assembled to form a cylindrical housing as shown in Fig. 1. The housing sections 18, are made interchangeable, consequently they 40 are easily and quickly built up into a vertical retort and six of them will equal in height when assembled, one of the sections of the shelf tube which is inserted into the upper end of a group of each six of them as 45 the retort is erected. Each section 19, is provided with a plurality of groups of spirally-arranged shelves or ledges 19^A, the shelves of each group over-lapping those of the next succeeding group.

50 Consequently by the use of these section- alized inner cylindrical members, retorts of different heights and of different tonnage capacities per day can be built.

The outer brick casing of the retort is 55 made of greater diameter than the sectional cylinder that surrounds the shelf-tube 10 to form a flue space 22 all around it, for the heat and the products of combustion which flow from the fire-box through a flue 23 into 60 it. The lower end portion of the flue 22, is provided with baffle ledges 22^A, which are constructed by extending a semicircular course of bricks inward into engagement with the sectional cylinder. These semicircular baffles are formed on opposite sides of

the flue, those on one side alternating with those on the opposite side. These baffles cause the heat to travel in a zig-zag course, and thus prevent it from traveling on one side of the flue only.

70

The flue 22, that is formed between the outer brick casing and the cylindrical housing of the shelf-tube extends to close to the top of the retort and then branches off to one side at an upward angle 24, and extends 75 to the top of the brick work of the retort, where a smoke stack 25, that is provided with a damper 26, is connected to it.

The vertical group of housing rings 19, that forms a surrounding cylinder for the 80 inner shelf-tube, terminate even with the top of the brick work 27, and a flat ring 28, is placed in the recess of the upper flange of the upper housing ring.

This flat ring 28, surrounds the shelf-tube 85 and the aperture through it is enough larger than the shelf-tube to allow crushed and pul- verized oil shale to flow freely through the space between the outside surface of the shelf-tube and the inside periphery of the 90 ring.

The shelf-tube extends above the ring 28, a short distance, and the hub of a sprocket wheel 29, is secured thereon, which is connected with a power source, not shown. An 95 annular rim 29^A is formed on the sprocket wheel, and a circular hopper 29^B is placed over the rim 29^A. Crushed oil shale is fed to the hopper through a chute 29^C. While I have illustrated a sprocket wheel as a means 100 of turning the tube, it will be apparent that any other means of accomplishing the object may be employed. The sprocket wheel is connected to the tube by set screws 30, and the wheel is formed with a series of openings 105 31, between its hub and toothed portion, which permit the passage of material from the hopper to the interior of the tube.

This hopper 29^B revolves with the wheel, and the shale fed thereto is evenly distrib- 110 uted into the top of the tube, and in order to accomplish this I preferably mount the sprocket wheel on ball-bearings in the following manner: The under side of the

sprocket wheel hub is in the form of a track 115 34, having a ball roll therein, and a ring 35, having a ball roll therein, which is supplied with balls, is formed on the ends of arms 36, that are a part of an annular feed spout 37, the lower end of which rests on top of the flat plate 28. The upper end of the spout 37, fits loosely around an annular rim 39, formed on the under side of the sprocket wheel, the spout being stationary. The track 34, of the sprocket wheel, rests on the balls 120 in the ring 35, thus permitting free rotation of the tube on the said ring 35. A flanged ring 40, is adjustably secured to the tube, a short distance above the ring 28, and to the under side of the ring 40, plows or scrapers 125 130

41. are secured, which push the shale off the plate 28, and into the space between the tube and the sectional cylinder 18.

The feed spout 37. is provided with openings between its arms 36. as shown in Fig. 9., and the pulverized oil-shale feeds from this spout through these openings, and falls, onto the shelves 11 and 19^A of the inner and outer cylinders, respectively, and is carried 10 around the space between them in a spiral path, the shale being pushed from the ledge 11, onto the ledges 19^A and vice-versa, throughout its downward course, until it finally lodges on a sealing plate 42 at the 15 lower end of the sectional cylinder 18. which is provided with an outlet opening 43.

The outlet opening 43 connects with a conveyer tube 44. that extends out through a portion of the wall of the retort, that forms 20 a temporary closure X, for an opening in the wall of the retort. A spiral conveyer 45. is mounted in this conveyer tube on a shaft 46. that projects beyond its outer end and a belt pulley 47. is mounted on the outer end of the 25 shaft 46. The outer end of the conveyer is closed but a discharging spout 47^A is placed in the upper side of the conveyer tube at its outer end.

The floor ring 42. prevents the shale tailings sand that reaches the bottom of the space between the shelf-tube and its housing cylinder, from falling to the floor of the stack 8. The material that reaches the plate 42. comprises a tailings gangue sand product 35 from which the petroleum oil and other volatile products have been sublimated in its falling action from the feed hopper to this floor ring, and the sublimated gas product flows from the feed-way space between the 40 inner and outer cylinders through a multiple series of pipes 48. that are connected at one end to the apertures 49. formed through alternate sections of the housing cylinder 18. These pipes 48. extend to and are connected 45 to the adjacent ends of a series of long horizontally arranged condensing chambers 50. which are also connected by vertically arranged pipes 51. at their opposite ends, with a long oil reservoir storage and discharging 50 tube 52. that is provided with a plurality of drip pipes 53. that are separated from each other by partitions 54. that extend across a portion of the lower part of this reservoir tank.

55 This oil reservoir 52. naturally receives some uncondensed gas, and it is provided at one end with a gas outlet pipe 55. that extends into and through the front wall of the fire-box so that it will discharge gas into 60 the fire-box over the grate bars, when it is desired to feed fuel gas to the fire-box.

The reservoir 52. is also provided at its opposite end with a gas outlet pipe 56. from which the gas may be allowed to escape or 65 may be conveyed away and used as desired.

The oil-shale treating retort contemplates a substantial manner of supporting a number of the lower sections of the cylinder 18, independently of the remaining upper sections, and I also construct the lower portion 70 of the retort in such a manner that an operator can enter through the brick work to the interior of the brick stack, to remove any fire-worn sections and to replace them. I preferably carry out this feature of my invention in the following manner:

The brick walls at the bottom of the retort on the opposite side from the fire-box is reinforced or buttressed for a portion of its height as shown at 57. in order that the 80 stack may not be weakened where the opening occurs, which has the temporary filling X. One of the outer cylinder sections, preferably the seventh section from the bottom, is formed with three projecting feet 58.—see 85 Fig. 3—which rest upon the adjacent course of brick in the stack, and this section 59. supports all of the sections above it, the sections below the section 59. being removable, and are supported in a manner to be presently described. A plate 60. is secured to the plate 42. and the plate 60. is formed with an annular channel into which the lower end of the tube 10 extends, and the material on the plate 42. works into this channel, and 95 surrounds the lower end of the tube thus sealing the same. A fire clay flue 61. extends from the fire-box, and has an unturned end which enters the axial opening in the plate 60. and this flue carries the heat from 100 the fire-box into the tube 10.

The temporary closure X is built into the opening of the wall, after the parts of the retort have been assembled, and it remains until it is necessary to remove the lower sections of the retort, when the said temporary closure is removed to afford access to the interior of the stack.

Upon the foundation or floor of the stack are secured three track rails 62 that extend 110 from the back of the brick casing through the opening and beyond the retort a short distance. On these three rails I mount a truck 63. that consists of the axles 64. and truck wheels 65.

On the axles I place a plate 66. on which angle irons 67. are secured at its opposite sides, each of which has a long arm member 68. that extends vertically above the track, and a horizontal inverted channel plate 69. 120 is supported on the truck between the arms 68.

Vertically positioned adjustment bolts 70. are extended loosely through the channel plate 69., the lower ends of which are threaded, and washer nuts 71. are threaded to them and rest on the top of the channel bar.

The upper ends of these adjusting bolts bear against the under side of the circular channel plate 60. and thus support all of the 130

sections of the outer cylinder below the section 59. This circular trough ring 60, centralizes and confines the lower end of the shelf-tube 10., and the plate 42. to which it is 5 secured supports the bottom sections of the housing cylinder that surrounds the shelf-tube.

Six of these sections are shown supported by the circular plate 42. and by means of the 10 bolts 70. these six sections can be raised until the upper one is pressed up against the section 59. thus preventing the products of combustion from the fire-box that flows through the flue 22. from entering the interior of the 15 cylinder surrounding the shelf-tube.

The plate 42. is provided with downwardly projecting channel bars 72. that are positioned to extend around the outer sides of the vertically projecting arms 67. of the 20 truck. They are arranged and adapted to act as confining and truck holding slideways and guideways on these arms to steadily hold the plate 42. and the retort cylinders and truck with its members in alinement with 25 each other. Consequently when erecting a retort the sections of the shelf-tube and sections of the housing cylinder are plumbed up by this adjustable truck supporting mechanism and that part of it that includes 30 the truck and the several cylindrical housing rings can lie set up on the truck and can be plumbed up outside of the retort if desired and then can be run into the brick casing.

This arched opening is closed up after the 35 installation of the truck and its adjusting apparatus and the cylinders and after the completion of the retort, except that if desired a small air admitting and regulating door which I do not illustrate may be placed 40 in it.

The interior of the shelf-tube forms principally an oil-shale heating and roasting flue by the heat from it that penetrates it and its shelves into the space between it and its surrounding housing cylinder and it also acts as and forms a smoke-stack the same as the outside flue 22. formed between the surrounding sectional housing cylinder and the inside wall of the brick casing which in addition to being a smoke-stack is naturally an oil-shale heating flue by the heat of radiation passing through the shell of the housing cylinder 18.

Consequently there are two oil-shale heating and roasting flues that heat, roast and sublimate the oil-shale and they operate from opposite directions and against opposite sides of the oil-shale in its falling passage down through the retort as will be more 55 fully explained hereinafter.

The heat of the fire-box is drawn by the natural draft induced by the shelf-tube, through the flue 61. and into the said tube.

There are three of the supporting bolts 60. and they have sprocket wheels 73. rigidly

mounted thereon, which are connected by a sprocket chain 74. By this means, the bolts are all turned simultaneously.

The condensers are made of sheet metal and they decrease in length and consequently 70 in capacity from the upper one down to the lowest one and they may be supported in their vertical position and arrangement by any suitable means. I do not illustrate, however, any means of supporting them, as 75 they may be entirely housed with the retort in a suitable mill building. They are partitioned at a short distance apart throughout the height of the retort and a sufficient number of them are used to insure 80 that rapid and practically complete condensation of the gases will be effected.

The operation of my oil-shale treating retort and its sublimating apparatus is as follows:

Oil-shale rock is crushed and pulverized 85 to preferably from about a quarter inch mesh to about twenty mesh, depending on the quality as to hardness and the various elements in the shale, the pulverizing to be- 90 tween four and eight mesh is preferable.

The oil-shale rock after having been crushed and pulverized to the desired mesh is fed into the hopper from a source of supply through the ore chute and from the hopper into the space between the upper ends of the two cylinders and upon the spirally arranged shelves of the shelf-tube and sections 95 19.

In order to feed the oil-shale evenly 100 through the circular opening between the sublimating cylinders I preferably rotate the hopper 29^B, together with the tube 10. by means of suitable power transmitting mechanism which is connected to the sprocket 105 wheel 29 in any suitable manner, but which I do not illustrate.

The pulverized oil-shale falls from the rotating hopper and its fixed circular spout down through the retort, and as it falls it 110 lodges on the upper surfaces of the shelves of the inner and outer cylinders all the way down to the floor ring plate at the bottom of these two roasting and sublimating cylinders, practically all of the oil-shale that 115 lodges on the shelves will have all of its volatile elements sublimated and volatilized in a very few minutes after it is fed into the retort. The shale is carried around and down the retort in a spiral path, and that 120 lodging on the ledges of the inner cylinder, is scraped off by the ledges of the outer cylinder, and vice-versa, the shale thus undergoing an intermittent dropping movement throughout its downward course, and by this means is thoroughly and evenly subjected to heat of a continuously increasing 125 temperature until it reaches the bottom plate 42. The material that is carried down through the retort is the rock matter of the 130

oil-shales which is called its tailings or gangue matter and which rolls easily off of the tops of the shelves of the cylinders after the volatile elements in it pass from it into 5 gas, this tailings material falls to the floor plate ring between and at the bottom ends of these cylinders and is discharged as a spent residue through and by the spiral conveyer; consequently the volatile elements of 10 oil-shale are sublimated quickly by indirect heat that radiates from the heat and smoke conveying flues through the shelves of the shelf-tube and its surrounding sectional housing cylinder and the products of combustion 15 from the fire-box do not come in direct contact with them as the oil-shale as it feeds through the retort is shielded from them.

My invention contemplates the use of any 20 kind or character of condensing apparatus adapted to condense the gases liberated in my retort. I preferably use, however, the condensing apparatus illustrated and described, as it forms a coöperating part of my 25 oil-shale treating retort, as the gases are immediately and continuously condensed into commercial products, and with the retort makes a simple practical and economical apparatus, of large tonnage treating capacity, and while I have illustrated its 30 preferred construction and arrangement, changes can be made in it without departing from the spirit of my invention.

My present invention represents a new 35 type of oil-shale treating retort, different from the apparatus patented by me in Letters Patent No. 1283723 and issued to me November 5, 1918.

Having described my invention, what I 40 claim as new and desire to secure by Letters Patent is:—

1. A vertical retort for sublimating the volatile elements of oil-shale, comprising a group of three cylinders within each other, 45 the outer cylinder of which forms a casing for the other two, the inner cylinder of said group being provided with an axial heat conveying flue, said retort being also provided with a heat conveying flue between 50 its outer cylindrical casing and the middle cylinder, a fire-box connected to the flues of said retort for heating said cylinders, said two inner cylinders being arranged with an oil-shale feeding space between their 55 adjacent surfaces and means for feeding oil-shale into the space between said inner cylinders, and for rotating said inner cylinder.

2. A vertical retort for sublimating the volatile elements of oil-shale, comprising a 60 group of three cylinders, within each other, the outer cylinder of which forms a casing for the other two, the inner cylinder of said group being provided with an axial heat conveying flue, said retort being also provided with a heat conveying flue between its

outer cylindrical casing and the middle cylinder, a fire-box connected to the flues of said retort for heating said cylinders; said two inner cylinders being arranged with an oil-shale feeding space between their adjacent surfaces and means for revolving the inner cylinder in said outer cylinder; said oil-shale feeding space being provided with thin overlapping spirally arranged shelves throughout its length adapted to receive the 70 falling ore-shale, and means, including a revoluble hopper, for feeding oil-shale between said cylinders, evenly into and throughout their annular entrance.

3. A vertical retort for sublimating the volatile elements of oil-shale, comprising a group of three cylinders within each other, the outer cylinder of which forms a casing for the other two, the inner cylinder of said group being provided with an axial heat 85 conveying flue, said retort being also provided with a heat conveying flue between its outer cylindrical casing and the middle cylinder, a fire-box connected to the flues of said retort for heating said cylinders, 90 said two inner cylinders being arranged with an oil-shale feeding space between their adjacent surfaces and means for feeding oil-shale into the space between said inner cylinders, said inner cylindrical member extending in a smoke stack portion above said retort, and an independent smoke stack connected to the flue between said middle cylinder and the outer cylindrical casing of said retort and means for rotating said inner 95 cylinder.

4. In a retort for treating oil-shales, the combination of the fire-box, the brick casing, and the inner shelf-tube and its housing cylinder provided with an annular flue 105 space around them, said shelf-tube and its housing cylinder being arranged to form an annular feedway space between them along the shelves of said shelf-tube, and means for feeding oil-shale evenly into the annular 110 feedway between said cylinders; means for withdrawing the residue from the bottom of said feedway; and means for operatively heating said flues, said oil-shale feeding means comprising a revoluble hopper surrounding the top annular entrance to the feedway of said cylinders; and an annular distributing chute below said hopper arranged to discharge the oil-shale in a circumferential stream into the annular feedway between said cylinders onto said shelves, a floor ring at the bottom of the feedway in 115 said cylinders and means including a conveyer for discharging the treated oil-shale from the bottom of the feedway of said feed cylinders.

5. In a retort of the character described, the combination with a stack and a combustion chamber connected therewith, of a hollow cylindrical member in said stack and 130

- spaced therefrom to form a surrounding flue, said cylinder having overlapping, inwardly extending, spirally arranged ledges; a revoluble flue within the cylinder and spaced therefrom having outwardly extending, overlapping, spirally arranged ledges, and means for feeding material into the space between said revoluble flue and the surrounding cylinder, said ledges being adapted to catch, agitate and drop the material step by step, in its passage down the retort, a conveyer at the lower end of the retort for removing the material, and a flue extending from the combustion chamber into the lower end of the revoluble flue.
6. In a retort of the character described, the combination with a combustion chamber and a stack connected therewith, of a hollow cylindrical member within the stack and spaced therefrom to form a surrounding flue, said cylindrical member being made up of individual sections which fit one within another, one of said sections being supported in said stack, thereby to support all of the sections above it, a truck at the bottom of the stack, an adjustable platform on the truck for supporting the sections below that section which is supported by the stack, a revoluble flue within the sectional cylinder and spaced therefrom, said sectional cylinder and revoluble flue being provided with spaced, over-lapping, spirally-arranged, co-operating, agitating ledges, means for feeding materials into the space surrounding the revoluble flue, and upon said ledges a conveyer leading from the lower end of said
- space and a flue leading from the combustion chamber into the lower end of said revoluble flue, said material being conveyed by the ledges, in a step by step, spiral path down the retort.
7. In a retort of the character described, the combination with a combustion chamber having a stack leading therefrom, of a sectional, tubular member supported in and spaced from the stack to form a surrounding flue space, a circular stationary feed spout on the top of the stack, a power driven wheel rotatably mounted on said feed spout, a tubular flue secured within the hub portion of said wheel, and extending down through said sectional cylinder, and spaced therefrom, means for feeding material to the space surrounding the revoluble flue, a flue connecting the combustion chamber with the lower end of the revoluble flue, a conveyer leading from the lower end of the space surrounding said revoluble flue, said sectional member and revoluble flue being provided with spaced, overlapping, spirally arranged, co-operating, agitating ledges which convey the material in a step by step spiral path, down the retort, condensing elements, and pipes connecting the space traveled by the ore with said condensing elements. 65

In testimony whereof I affix my signature in presence of two witnesses.

JOHN H. GALLOUPE.
